UNITED STATES PATENT OFFICE.

HARRY S. TOWNSEND, OF PHILADELPHIA, PENNSYLVANIA, ASSIGNOR TO
FRIEDBERGER MANUFACTURING COMPANY, OF PENNSYLVANIA.

DESIGN FOR TRIMMING FOR LADIES' UNDERWEAR.

SPECIFICATION forming part of Design No. 34,597, dated May 28, 1901.

Application filed April 24, 1901. Serial No. 57,342. Term of patent 3½ years.

To all whom it may concern:

Be it known that I, HARRY S. TOWNSEND, a citizen of the United States, residing at Philadelphia, county of Philadelphia, and State of Pennsylvania, have invented and produced a new and original Design in Trimmings for Ladies' Underwear, of which the following is a full, clear, and exact description, reference being had to the accompanying drawing, which forms a part of this specification.

My invention has for its object the provision of a new and original design for trimming or edging, and is especially adapted to be used for ornamenting ladies' underwear.

The figure is a front view of a portion of such trimming.

The invention consists of the heading, the body, the ribbon-space, and the tip.

The heading A is of the plain inlay or gimp-like type, backed by parallel rows of chains.

The body B consists of rows of chain-like threads intersecting each other, the chains extending transversely of the edging being

wider and farther apart than the chains extending along the length of the edging. 25

The ribbon-space C is of open-work effect, having a series of transverse bars.

The tip D consists of a series of threads extending the length of the fabric, some of which are straight and others staggered, 30 these threads being interlaced by transverse threads extending back and forth between the lengthwise threads.

Having now fully described my invention, what I claim, and desire to protect by Letters Patent, is—

The design for trimming for ladies' underwear, substantially as shown and described.

In testimony of which invention I have hereunto set my hand at Philadelphia on this 17th 40 day of April, 1901.

HARRY S. TOWNSEND.
